JOHN PRENTICE, OF BAYONNE, NEW JERSEY, ASSIGNOR TO THE BABCOCK & WILCOX COMPANY, OF BAYONNE, NEW JERSEY, A CORPORATION OF NEW JERSEY.

SAFETY VALVE.

Application filed March 7, 1928. Serial No. 259,718.

This invention relates to a safety valve for a steam boiler that is provided with a superheater for the steam. In such boilers there is a drop in pressure between the saturated steam in the boiler drum and the superheated steam passing out of the superheater due to the friction in the superheater. It is important that the superheater safety valve shall open before the saturated steam safety valve on the boiler drum which is first to open. It is also important that the range of setting between the superheater safety valve and the saturated steam safety valve which is the first to open shall not be too great as this results in a loss due to an undue lowering of the pressure leaving the superheater below that for which the boiler is built. By the present invention the saturated steam pressure is utilized in part for the opening of the superheater safety valve and the arrangement is such that the superheater safety valve will open when the steam in the steam and water drum reaches a predetermined pressure irrespective of what the pressure at the superheater outlet may be through the loss of pressure due to the friction of the steam in flowing through the superheater. By making the predetermined pressure, say 10 lbs. per sq. in. below that at which the first saturated steam safety valve will open, the desired result of having the superheater safety valve to be the first to open will be accomplished.

The invention will be understood from the description in connection with the accompanying drawing, in which Fig. 1 is a vertical section on an enlarged scale of an illustrative embodiment of the invention along the line 1—1 of Fig. 2; Fig. 2 is an outside view of the assembled safety valve partly broken away to show the method by which the valve is mechanically operated by levers and fulcrums to test its condition from time to time, and Fig. 3 shows a cross section along the line 3—3 of Fig. 2.

In the drawings reference character 5 indicates a valve casing which may be attached to a superheater outlet or any other convenient place where superheated steam at the pressure of the superheater outlet exists. This valve is provided with the usual valve disc against which the superheated steam presses tending to open the same. The outlet 6 from the casing 5 is for conveying away the waste steam when the valve in the cas-

ing 5 opens. The valve stem 7 extends upwardly to the outside of the valve casing and a disc 8 is attached to the stem 7 a short distance from the casing. A compression spring 9 surrounds the valve stem and its upper end presses against a disc 10 that is seated upon the end of an externally threaded sleeve or guide 11 for the valve stem.

A frame 12 around the valve stem 7 is seated upon the valve casing 5 and its upper portion 13 is provided with a central threaded hole into which the guide 11 is screwed. A nut 14 is threaded upon the upper threaded end of the valve stem 7 and is held in place by means of a cross pin 15.

A housing 18 has a lower flange 19 by which it is bolted to the upper portion of the frame 12. A pivot pin 20 is mounted on a lug at one side of the lower end of the housing 18 and two parallel spaced levers 21 have one end of each pivoted to the pivot pin 20. The other ends of the levers 21 are provided with a cross pin 22 to which one member 23 of a toggle is pivoted. The member 23 of the toggle is pivoted to the other member 24 of the toggle which is in turn pivoted at 25 to the lower portion of the frame 12. A support 26 projects outwardly from the same side of the frame 12 and a lever 27 is pivoted thereto as shown at 28. The upper cam portion 29 of the lever 27 bears against the joint of the toggle as shown at 30 to straighten the toggle and lift the left hand end of the levers 21 for a purpose to be described below.

The upper end of the housing 18 is provided with a flange 31 to which the flange 32, having a boss 33, is bolted by means of the stud bolts 34. A gland 35 is screwed into an internally threaded hole in the boss 33.

An opening 36 for saturated steam extends into the upper solid portion of the housing 18 and an opening 37 for superheated steam extends into a chamber 37' in the upper portion of the housing 18. Internally threaded rings 38 and 39 are located in the chamber 37' and discs 40 and 41 threaded on their peripheries are screwed into the rings 38 and 39. The disc 38 is provided with a lower threaded extension 42 and a central opening 43 extends through the disc and a portion of the extension 42 and communicates with a cross opening 43' that communicates with a recessed chamber 42' to which the opening 36 leads. A flat threaded nut 44 and a py-

ramidal jamb nut 45 are provided for the threaded end of the extension 42 and a gasket 46 may be placed below the disc 40, as indicated, to prevent leakage when the nut 44 is tightened. The jamb nut 45 operates as a stop to limit the upward travel of the valve stem 7 and can be adjusted to different positions for that purpose.

A bellows 47 of a well known type is located in the chamber 37' in the upper portion of the housing 18 and has flanges 48 at the ends of the bellows that are clamped between flanges 49 on the rings 38 and 39 and the discs 40 and 41. The effective external end area of the bellows 47 is preferably made approximately equal to the area of the valve disc at the lower end of the stem 7. An external groove 50 is provided on the ring 38 and a cylinder 51 may have a rib rolled into this groove. The cylinder 51 extends upwardly to enclose the bellows 47 and ring 39. The disc 41 is provided on its upper side with a central boss 55 and a rod 56 provided with an opening 57 around the boss 55 extends through the boss 33, a recess 58 being left to permit the enlarged lower end of the rod 56 to move longitudinally.

A cross bar 59 extends across the upper end of the rod 56 and is provided with a recess into which the upper end of the rod extends. Rods 60 on opposite sides of the housing 18 have their upper ends held to the ends of the cross bar 59 in adjustable positions by means of the nuts 61. The rods 60 may pass through guide holes in the flanges 31 and 32. A pair of cross bars 62 extends through the housing 18 and are attached to the lower ends of the rods 60 by means of the bolts and nuts 63 and 64.

40 The operation is as follows: Superheated steam or steam at the pressure at the superheater outlet enters the chamber 37' through the opening 37, and surrounds the outside of the bellows 47 while steam at the pressure of 45 the saturated steam enters through the openings 36 and 43 into the inside of the bellows 47. Superheated steam also entering the valve casing 5 presses against the lower side of the valve disc on the valve stem 7 tending 50 to open the same. When the pressure of the superheated steam in the valve casing 5, supplemented by the differential of pressure on the outside and inside of the bellows 47, is sufficient to overcome the spring 9, the valve is 55 opened and excess steam escapes to lower the pressure. The guide 11 can be screwed in to different distances for the purpose of adjusting the tension of the spring 9 and thereby regulating the pressure at which the valve 60 will open. The differential in pressure on the outside and inside of the bellows 47 operates to aid in opening the valve in the casing 5 because the higher pressure of saturated steam inside the bellows forces the disc 41 65 against the rod 56 which forces the cross bar

59 upwardly thereby carrying the cross bars 62 upwardly by means of the rods 60, thus causing the nut 14 on the valve stem 7 to be pressed and aid in opening the valve.

The lever 27 can be used whenever desired 70 to open the valve manually in the casing 5 by causing the cam portion 29 to partially straighten the toggle members 23 and 24, thus raising the lever 21, cross bars 62, nut 14 and valve stem 7.

The arrangement of the bellows and associated parts in the chamber 37' is such that the same can be removed for repair and replacement due to the fact that the flange 32 and boss 33 are bolted to the flange 31 at the upper end of the chamber 37'.

I claim:

1. In a safety valve for a steam boiler that produces saturated steam and superheated steam, a spring pressed valve disc having a 85 stem, means to cause superheated steam to press against the face of said valve disc and means for causing differential pressure between the saturated and superheated steam to press against said valve stem. 90

2. In a safety valve for a steam boiler that produces saturated steam and superheated steam, a spring pressed valve disc having a stem, means to cause superheated steam to press against the face of said valve disc and 95 means for causing differential pressure between the saturated and superheated steam to press against said valve stem, said differential pressure being obtained from an area approximately equal to the area of said valve 100 disc.

3. In a safety valve for a steam boiler that produces saturated steam and superheated steam, a spring pressed valve disc having a stem, means to cause superheated steam to 105 press against the face of said valve disc, means for causing differential pressure between the saturated and superheated steam to press against said valve stem, and means to limit the extent of travel of said valve disc. 110

4. In a safety valve to be operated by saturated steam at one pressure and superheated steam at a lower pressure, a spring pressed valve disc, a bellows, means for leading superheated steam to said valve disc and saturated steam to the inside of said bellows to operate 115 said valve.

5. In a safety valve to be operated by saturated steam at one pressure and superheated steam at a lower pressure, a spring pressed 120 valve disc, a bellows, means for leading superheated steam to said valve disc and to the outside of said bellows and saturated steam to the inside of said bellows to operate said valve.

6. In a safety valve to be operated by saturated steam at one pressure and superheated steam at a lower pressure, a spring pressed valve disc, a bellows, means for leading superheated steam to said valve disc and 125 130

saturated steam to the inside of said bellows to operate said valve, and a stop to limit the extent of travel of said valve disc.

7. In a safety valve to be operated by saturated steam at one pressure and superheated steam at a lower pressure, a spring pressed valve disc, a bellows connected to said valve disc, said bellows being surrounded by superheated steam and filled with steam at the 10 pressure of the saturated steam.

8. In a safety valve to be operated by saturated steam at one pressure and superheated steam at a lower pressure, a spring pressed valve disc, a bellows, means for leading superheated steam to said valve disc and saturated steam to the inside of said bellows, the effective area of said bellows being approximately equal to the area of said valve disc.

9. In a safety valve to be operated by saturated steam at one pressure and superheated steam at a lower pressure, a spring pressed valve disc, a bellows having a vertically guided movement, means for leading superheated steam to said valve disc and saturated steam to inside of said vertically guided bellows, the effective external end area of said bellows being approximately equal to the area of said safety valves.

10. In a safety valve to be operated by saturated steam at one pressure and superheated steam at a lower pressure, a spring pressed valve disc, a bellows having a vertically guided movement, means for leading superheated steam to said valve disc and saturated steam to inside of said vertically guided bellows, the effective external end area of said bellows being approximately equal to the area of said safety valves, and means provided whereby the upward movement of bellows may be varied and fixed.

11. In a safety valve to be operated by saturated steam at one pressure and superheated steam at a lower pressure, a spring pressed valve disc, a bellows having a vertically guided movement, means for leading superheated steam to said valve disc and saturated steam to inside of said vertically guided bellows, the effective external end area of said bellows being approximately equal to the area of said safety valves, the arrangement of the bellows and related parts and their housing being such that they may be removed for repairs without interfering with the operation of the superheated safety valve to which it is attached.

JOHN PRENTICE.
